BOOK CONSTRUCTION

Frank Stanley Schade, Holyoke, Mass., assignor
to National Blank Book Company, Holyoke,
Mass., a corporation of Massachusetts

Application June 26, 1935, Serial No. 28,420

8 Claims. (Cl. 281--19)

In the manufacture of books, particularly of the blank book type, it has heretofore been proposed to make the bound portion removable from the cover of the book, so that a single cover may 5 be used for a plurality of different fillers; and many different constructions have been proposed for this end. In my prior application Serial No. 754,456, filed November 23, 1934, I have described a construction in which a helical wire is used for 10 securing the stack of paper sheets, the wire being secured to the inside of the back of the binding by a rod passing within the wire coil and underneath struck-up loops or arches extending from the back of the binding at intervals between 15 the coils. One difficulty with this type of construction, particularly when it has been employed on books having a flat back panel, has been in the maintenance of a substantial degree of 20 rigidity of the helical wire coil in a sideways direction; the coil evidencing a tendency to rock upon the back panel and giving an undesirable looseness in the appearance of the book as a whole. It is the purpose of the present invention to provide a construction in which this 25 undesirable looseness will be avoided, and in which a firm union of the helical wire coil and the binder-carried backing plate can be attained with simple means. It is a further purpose to improve upon the assembling means 30 previously proposed with respect to the ease and rapidity with which the parts can be put together.

The invention will now be described with reference to the accompanying drawing, in which— 35 Fig. 1 is a plan view of a book embodying the invention, the book being shown open and with its component parts partially broken away;

Fig. 2 is a detail section, on an enlarged scale, through the helical wire coil and its attaching 40 means; and

Fig. 3 is a side view showing a detail of the wire coil and its attaching means.

In the manufacture of the improved book made in accordance with the present invention there 45 is employed a plate 10, which in the form shown is preferably flat so as to accord with the flat back panel of one commercial type of blank book. This plate is secured in any standard or desired way to a book cover 11, the details of which need 50 not be described as they form no part of the present invention. As shown, the book cover is provided with a lining 12 extending across the plate 10, but this lining may be omitted or terminated short of the plate, as may be desired for 55 particular designs. The plate 10 is formed with

loops or arches 13, which may be stamped or struck up from the body of the plate in the manner best shown in Figs. 2 and 3; and which are preferably of a width equal to the spacing between adjacent coils of the wire helix so as to give support thereto in a longitudinal direction in a manner which will be fully discussed later on. If the lining 12 is used, the arches 13 of course stick up through it, the lining being suitably apertured for that purpose.

The arches 13 are spaced apart a distance preferably corresponding to a multiple of the distance between successive coils of the wire helix 14, which has been threaded through holes 15 in the sheets of a paper stack 16 so as to form the 10 binding therefor. This degree of spacing avoids any necessity of stretching or contracting the coils of the wire helix, a matter of considerable importance on account of the effect of a distortion of the helix in preventing smooth turning 20 over of the leaves of the stack. The width of the arches is, as pointed out above, preferably equal to the space between adjacent coils, thereby further avoiding any distortion of the helix and assisting in giving it a firm anchorage in a manner 25 about to be described. A locking member 17 extends through the helix and underneath the loops 13 so as to bind the helix firmly against the back plate 10. At one end the member 17 has an upturned portion 18 which serves as a handle for 30 the member in inserting it in and removing it from the arches 13. At its end remote from the handle the member is adapted to contact with a stop 19 formed by bending up the end of the plate 10, so that the motion of the member into the position it assumes when holding the parts assembled will be limited. The stop 19 and the turned up portion 18 of the member 17 also serve as limiting abutments for the wire helix; on the one hand preventing any stretching of the helix and on 40 the other hand guarding the helix against being caught against other objects while the book is being handled.

As has been stated above, one difficulty with assemblies of this general type is their tendency 45 towards lateral instability. In the present case the member 17 is made of a special shape to increase this lateral stability to a degree such that the structure is entirely practicable even where a flat back plate is used. To this end the member 50 17 is made of sheet metal bent so as to be concave downwardly, the upper surface of the member being preferably convex on the same curvature as that of the inside of the loops 13, although other curved shapes or even an angular form 55

may be used if desired. As will be best seen from Fig. 2, the helix 14 is given by this means a three-point support which is conducive to the highest lateral stability possible for a given area of supporting surface, and lends itself in cases where great rigidity is required to an actual flattening of the coils between the member 17 and the plate 10. At its bottom the helix, whether flattened or not, rests upon the plate 10 or upon the lining 12 if this be continued over the plate. Spaced laterally on each side of this line of contact the coils of the helix are contacted with by the edges of the member 13. It will be apparent that as contrasted with the use of a round rod, which would give a contact with the coils directly above the contact which these coils have with the plate, there is in the form shown a double contact of the member 17 with the coils, one on each side of the line of contact of the coils with the back plate. With the round rod type of anchorage the rigidity of the helical coil in a sideways direction can only be attained in a high degree by a concave curvature of the back plate 10. In the present construction, on the contrary, any desired degree of rigidity can be attained, even with a flat back plate, by increasing the pressure with which the coils are pinched between the plate 10 and the member 17; with an actual flattening of the coils against the plate, if desired. This flattening would not be possible in the case of the round rod anchor, since in that case the pressure on the coils is along a single straight line.

One further factor contributing greatly to the stability of the assembled product relates to the form of the arches 13. As stated above, these arches are made of a width to exactly fill the spaces between the adjacent turns of the helical coil 14. It will be clear from a consideration of Figs. 2 and 3 that a direct longitudinal support is given to the adjacent coils by these arches; and since the coils of the helix are all interconnected these spaced supports will give a high degree of longitudinal stability to the coil considered as a whole. This longitudinal stability is also aided by the parts 18 and 19 which come at the ends of the helix and perform for these portions somewhat the same functions that the arches perform for intermediate portions. Of course if this degree of stability is not desired the arches may be made narrower or the end pieces omitted, while retaining the beneficial functions of the other features of the invention. It is preferred, however, to employ in combination all of the modes described by which stability, either longitudinal or lateral, is attained, as these modes when employed in combination act to mutually reinforce each other and a more satisfactory product is thereby attained.

A further advantage possessed by this type of construction is in its ease of assembly as contrasted with the use of a round rod as a securing means. It will be seen that in assembling the paper stack in the binder the securing member 17 must be threaded through a series of coils 14 and arches 13, and that any tendency to catch upon these parts will require more time and care in assembly. A round rod in order to go through the parts at all needs to be so small in diameter that no effective beveling of its forward end can be had. With the concave member 17, on the contrary, a considerable width and depth are available, and the forward end 20, as shown in Figs. 1 and 3, can be tapered up and down as well as sideways so as to make its entrance through the series of loops and coils very easy

while maintaining a tight engagement when the member has once been threaded in place.

The simplicity of the arrangement described will be apparent, as will also the great rigidity of the member 17 in proportion to its weight, this being due to the concave shape described above. This rigidity not only adds to the rigidity of the device as a whole after assembly, but prevents any tendency to buckling on the part of the securing member while it is being threaded into place.

Having thus described the invention in its preferred form, I will proceed to define its novelty both in its generic and its preferred forms in the following claims.

I claim:

1. In a book having a removable filler bound together with a helical wire coil, said coil being held by a securing member passing inside the coil and underneath arches formed in a back plate secured to the cover of the book, that construction of securing means in which it is shaped to contact with the wire coils along two lines spaced laterally from the central line of contact of the wire coils with the back plate.

2. In a book having a removable filler bound together with a helical wire coil, said coil being held by a securing member passing inside the coil and underneath arches formed in a back plate secured to the cover of the book, that construction of securing means comprising a member convex in cross-section so as to contact with the inside of the arches and having contact with the inside of the coil along lines spaced laterally from the central line of contact of the wire coil with the back plate.

3. In a book having a removable filler bound together with a helical wire coil, said coil being held by a securing member passing inside the coil and underneath arches formed in a back plate secured to the cover of the book, that construction of securing means comprising a sheet metal member bent into concavo-convex cross-section with its convex side in engagement with the inside of the arches and its concave side in engagement with the inside of the wire coil.

4. In a book having a removable filler bound together with a helical wire coil, said coil being held by a securing member passing inside the coil and underneath arches formed in a back plate secured to the cover of the book, that construction of securing means comprising a sheet metal member bent into concavo-convex cross-section with its convex side in engagement with the inside of the arches and its concave side in engagement with the inside of the wire coil, one end of said member being provided with a bent portion serving as a handle and the other end of the member being tapered to facilitate its entrance into the spaces between the coil and the loops.

5. In a book having a removable filler bound together with a helical wire coil, said coil being held by a securing member passing inside the coil and underneath arches formed in a back plate secured to the cover of the book, that construction of securing means comprising a member shaped to contact with the wire coil along two lines spaced laterally from the central line of contact of the wire coil with the back plate, and curved in at least two directions at its forward end to facilitate its entrance into the spaces between the coil and the arches.

6. In a book having a removable filler bound together with a helical wire coil, a back plate

having arches of a width so that each arch will completely fill the space between adjacent turns of the wire helix, and a member passing inside the coil and underneath said arches, the member being shaped to contact with the wire coil along two lines spaced laterally from the central line of contact of the wire coil with the back plate.

5. 7. In a book having a removable filler bound together with a helical wire coil, a back plate having arches of a width so that each arch will completely fill the space between adjacent turns of the wire helix, a member passing inside the coil and underneath said arches, the member being shaped to contact with the wire coil along two lines spaced laterally from the central line of contact of the wire coil with the back plate, and abutments at each end of the wire coil limiting the motion of the coil in an outward direction.

10. 8. In a book having a removable filler bound together with a helical wire coil, a back plate having arches of a width so that each arch will completely fill the space between adjacent turns of

the wire helix, a member passing inside the coil and underneath the arches, the member being convex in cross-section so as to contact with the inside of the arches and having contact with the inside of the coil along lines spaced laterally from the central line of contact of the wire coil with the back plate, the member being bent upwardly at one end to form a handle and to limit the outward motion of the adjacent end of the wire helix, and the back plate being bent upwardly 10 at the end remote from the handle on said member to form a stop for said member and to limit the outward motion of the adjacent end of the wire helix, the lateral stability of the wire helix being determined by the flattening pressure exerted on the helix by the gripping action of the member on the one hand and the back plate on the other hand, and the longitudinal stability of the helix being enhanced by the contact of the arches with the adjacent turns of the helix. 15 20
